R. G. TURNER

FRICITION LET-OFF FOR LOOMS

Filed March 19, 1925

UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FRICTION LET-OFF FOR LOOMS.

Application filed March 19, 1925. Serial No. 16,800.

This invention relates to let-offs for looms and an object of the invention is to provide a let-off so constructed as to permit the warp to be turned back when "picking out" by mechanism which will create a tension on the warp no greater than the normal operating tension.

When weaving certain fabrics such as duck it occasionally happens that a miss pick occurs, requiring the weaver to "pick out" all the picks between the fell and the defective pick. After these picks have been removed it is necessary to move the cloth backwardly in the loom until the fell is in line with the reed before weaving is resumed. It is highly desirable that the warp tension be the same after the pick-out as it was before so that a mark will not appear on the cloth. The weaver usually releases the friction and turns the beam back by hand but with such a method there is never any assurance that the warp tension will be proper. It is also necessary to be able to release the tension of the warp so that the cloth can be moved forwardly, as when a shuttle smash occurs.

It is accordingly a further object of my invention to provide hand operated mechanism by which the beam may be turned backward or forward to meet either of the conditions already mentioned without requiring such nicety of adjustment as is necessary with the prevailing methods for accomplishing the same result.

With these and other objects in view which will appear as the description proceeds, my invention resides in the combination and arrangement of parts hereinafter described and set forth in the claims.

In the accompanying drawings wherein I have shown one form of my invention,

Fig. 1 is an end elevation of a loom having my invention applied thereto,

Fig. 2 is a vertical section on line 2-2 of Fig. 1, and

Fig. 3 is an enlarged vertical section on line 3-3 of Fig. 2.

Referring more particularly to the drawings it will be seen that I have provided a loom frame 10 having the usual crank shaft 11, connector 12, and lay 13. The rear part of the frame is provided with pockets 14 which receive the gudgeons 15 of a warp beam W. Secured to the warp

beam and concentric with the gudgeons 15 are gears 16 by means of which the beam may be turned either in a forward or a backward direction.

Spaced from the beam W is a shaft 17 mounted on supports 18 having secured thereto near one end thereof a worm gear 19 having an internal friction face 20. A worm 21 is secured to a forwardly extending shaft 22 and meshes with the worm gear 19. The ends of said shaft 22 are received by bearings 23 and the forward end thereof is provided with a hand wheel 24 by means of which said worm 21 may be turned in either direction.

Loosely mounted on each end of shaft 17 is a spider 25 having a pinion 26 cast integral therewith to mesh with the adjacent gear 16 and provided with a plate 27. Slots 28 are cast in each plate 27 to receive bolts 29, said bolts extending freely through the slots 28 and being held in position by nuts 30. Said bolts extend through wings 31 which are formed on friction sectors 32 and 33, respectively, one pair of sectors being located on each side of the loom. Said sectors are hinged together as at 34 and are provided with inwardly extending fingers 35 and 36, respectively, the finger 36 receiving a set screw 37 which presses against the finger 35 to expand the sectors, each of which has a leather facing 38.

The gear 19 has a hub 39 which is keyed as at 40 to the shaft 17 and a drum 41 is secured to that end of the shaft 17 opposite the worm gear 19 by a key 42. One pair 90 of sectors cooperates with face 20 of gear 19 and the other pair cooperates with face 43 of drum 41. Collars 44 prevent end motion of the gear 19 and drum 41.

The operation of my improved let-off will be apparent to those skilled in the art. During normal weaving the worm 21 will prevent rotation of the worm gear 19, shaft 17, and drum 41, and as the beam W and gear 16 continue to rotate the pinions 26 will be rotated to cause relative frictional movement between the leather facings 38 and the faces 20 and 43, respectively. The extent of the friction and therefore the tension of the warp can be regulated by varying the setting of the screws 37. When a misspick occurs and it is necessary to "pick out", the weaver will remove the picks until

the defective pick is reached, which will leave the fell of the cloth forward of the reed when the latter is on front center. When the picking out operation is completed the lay will be moved to forward position and the hand wheel 24 rotated so as to cause a backward or clockwise rotation of the beam W as viewed in Fig. 1 to move the fell of the cloth back to the reed. 5 The hand wheel 24 can be turned a short distance after the fell has reached the reed without putting undue tension on the warp threads inasmuch as the only pressure brought to bear upon the warp beam is 10 that which can be transmitted through the friction, and this is the same friction which resists forward movement of the beam. The warp threads will therefore be restored to their original tension and weaving may 15 be resumed without leaving a mark in the cloth.

If for any reason it is necessary to move the cloth forwardly in the loom this result can be accomplished by turning hand wheel 25 24 in the opposite direction. In so doing the warp is slackened without releasing the friction or its adjustment. The worm acts as a stop to hold the worm gear in any position.

30 From the foregoing it will be seen that I have provided a very simple friction let-off for looms so arranged as to permit the beam to be reversed without putting the warp threads under undue tension, because of the 35 fact that the reverse movement is accomplished by reversing the friction which normally resists forward movement of the beam and this friction is the same whether the beam be turning forwardly or rearwardly 40 and is not changed in any way during the picking out operation.

Having thus described my invention it will be apparent that changes and modifications 45 may be made therein by those skilled in the art without departing from the spirit and scope of the invention, and I do not wish to be limited to the details herein disclosed, but what I claim is:

1. In a let-off mechanism for looms, a 50 warp supply, a friction member movable with the supply as the latter supplies the demand of the loom for warp, a second friction member to cooperate with and resist the movement of the first named friction member and warp supply, and a reversing device connected to the second named friction member, said device effective to hold said second named friction member in fixed position during the normal running of the loom and 55 being effective to turn the second named friction member backwardly to reverse the direction of movement of the first named friction member and the warp supply connected thereto.

60 2. In a let-off mechanism for looms, a

warp supply, a friction member movable with the supply as the latter supplies the demand of the loom for warp, a second friction member to cooperate with and resist the movement of the first named friction member 70 and warp supply, and a reversing device connected to the second named friction member in fixed position during the normal running of the loom and being effective to turn the second named friction member backwardly to reverse the direction of movement of the first named friction member and the warp supply connected thereto while the same frictional contact is preserved between the members as exists 80 under normal running conditions.

3. In a let-off mechanism for looms, a warp supply, a friction member movable therewith as the supply moves to furnish the warp required by the operation of the 85 loom, a second friction member normally contacting with the first friction member, and a reversing device effective under normal conditions to hold the second named member in fixed position to cause the same to resist normal forward movement of the first named friction member and the warp supply, said reversing device being effective also to turn the second named member backwardly and by means of the normal friction 90 existing between the members to thereby cause reverse movement of the first named friction member and the warp supply connected thereto.

4. In a let-off mechanism for looms, a warp supply, a friction member movable therewith as the supply moves to furnish the warp required by the operation of the loom, a second friction member normally contacting with the first friction member, and a reversing device effective under normal conditions to hold the second named member in fixed position to cause the same to resist normal forward movement of the first named friction member and the warp supply, said reversing device being effective also to turn the second named member backwardly and by means of the normal friction existing between the members to thereby cause reverse movement of the first named friction member and the warp supply connected thereto, said device including a worm gear rigid with respect to the second named friction member and a worm cooperating with said worm gear and normally held in fixed longitudinal position.

5. In a let-off mechanism for looms, a warp supply, a gear movable with the first named gear, a friction element movable with the second named gear and comprising a substantially closed ring adjustable as to diameter, a second friction member cooperating with the first named member to resist movement thereof and the gears and warp supply, a worm gear fixed with respect to 130

the second named friction member, and a worm cooperating with the worm gear to hold the latter in fixed position under normal conditions and effective to move said worm gear backwardly to reverse the direction of movement of the first named friction member and the warp supply, the nor-

mal frictional contact between the members being maintained during the reversing movement.

In testimony whereof I have hereunto affixed my signature.

RICHARD GREENLEAF TURNER.
